M. O'BRIEN.

RAILWAY RAIL LOCK.

APPLICATION FILED AUG. 23, 1917.

1,244,072.

Patented Oct. 23, 1917.

FIG. 1.

FIG. 2.

FIG. 3.

Inventor

Michael O'Brien,

By his Attorneys

Edgar Gates Co.

UNITED STATES PATENT OFFICE.

MICHAEL O'BRIEN, OF JERSEY CITY, NEW JERSEY.

RAILWAY-RAIL LOCK.

1,244,072.

Specification of Letters Patent. Patented Oct. 23, 1917.

Application filed August 23, 1917. Serial No. 187,882.

To all whom it may concern:

Be it known that I, MICHAEL O'BRIEN, a citizen of the United States, and residing at Jersey City, in the county of Hudson and 5 State of New Jersey, have invented certain new and useful Improvements in Railway-Rail Locks, of which the following is a specification, such as will enable those skilled in the art to which it appertains to make 10 and use the same.

This invention relates to railway rail locks designed to prevent the spreading of the rails, or any lateral movement of one independent of the other; and the object 15 thereof is to provide an improved device of this class which is simple in construction, efficient in operation and which is also capable of application to railway rails having different transverse dimensions; and with 20 this and other objects in view the invention consists in a device of the class specified, constructed as hereinafter described and claimed.

The invention is fully disclosed in the following specification, of which the accompanying drawing forms a part, in which the separate parts of my improvement are designated by suitable reference characters in each of the views, and in which:—

30 Figure 1 is a plan view of a part of a railway track and showing my improved railway rail lock device in use;

Fig. 2 a section on the line 2—2 of Fig. 1; and,

35 Fig. 3 a view similar to Fig. 2 but showing a modification.

In the drawing forming part of this specification I have shown at *a* and *b*, the rails of a railway track which are mounted 40 on and secured to the cross ties *c* in the usual manner; and at *d* I have shown my improved railway rail lock device.

The rails *a* and *b* are of the usual form and provided with web portions *a*² and *b*² 45 respectively, and with base portions *a*³ and *b*³ having outer and inner flanges *a*⁴ and *a*⁵, and *b*⁴ and *b*⁵, and my improved railway rail lock device *d* comprises a bar composed of a top member *d*² and a bottom member *d*³, 50 and said top and bottom members are preferably composed of sheet steel or other suitable material, and the top member *d*² passes under the rail *a* at one end and said end is provided with a hook member *d*⁴ which over- 55 laps the outer flange *a*⁴ of the rail *a*, and

the opposite end of the top member *d*² is provided with a raised part *d*⁵ which overlaps the inner flange *b*⁵ of the base of the rail *b*, and the end portion of the top member *d*² which passes under the rail *a* is provided with a longitudinal slot *d*⁶. 60

The bottom portion *d*³ of the lock device *d* at one end passes under the rail *b* and is provided with a hook member *d*⁷ which overlaps the outer flange *b*⁴ of the rail *b*, 65 and the opposite end of the bottom portion *d*³ of the lock device is provided with an angular hook member *d*⁸ which passes up through the longitudinal slot *d*⁶, and overlaps and engages the inner flange *a*⁵ of the rail *a*, all as clearly shown in Fig. 2. The bottom portion *d*³ of the lock device is also provided between the end portions thereof with longitudinal slots *d*⁹ and bolts *e* are passed downwardly through the top member *d*² and through the slots *d*⁹ in the bottom member *d*³, and provided with nuts *e*² 70 and washers *e*³, and by means of this construction the top and bottom portions of the lock device are secured together and also 75 made longitudinally adjustable one upon the other.

With this construction it is necessary to provide means to securely lock the separate parts *d*² and *d*³ of the lock device against 80 longitudinal movement, and for this purpose I provide blocks *f* and *f*² which may be secured in the inner end portion of the longitudinal slot *d*⁶ for which purpose bolts *g* are employed, and it will be noted that 85 the block *f*² shown in Fig. 3 is smaller than the block *f* shown in Fig. 2, and by means of this construction my improved lock device may be used in connection with rails, 90 the base portions of which are of different 95 transverse dimensions.

With this device the rails, as will be understood, may be securely locked against what is known as "spreading" or against any lateral movement of one independent of 100 the other, and while I have shown and described the construction of my improved railway rail lock device which I prefer, my invention is not limited to the exact details thereof herein shown and described, and 105 changes therein and modifications thereof may be made, within the scope of the appended claims, without departing from the spirit of my invention or sacrificing its advantages.

Having fully described my invention, what I claim as new and desire to secure by Letters Patent, is:—

1. A railway rail lock device comprising a transverse bar member composed of top and bottom parts adjustably connected, the top part being adapted at one end to be passed beneath one rail and being provided with a hook member adapted to overlap the outer base flange of said rail, said top part being also provided adjacent to said end with a longitudinal aperture, and at the opposite end with a hook member adapted to overlap the inner base flange of the other rail, and the bottom part being adapted to be passed beneath the last named rail and being provided with a hook member adapted to overlap the outer base flange thereof and said bottom part being also provided at its opposite end with a hook member adapted to be passed upwardly through the aperture in the corresponding end portion of the top part and to engage the inner base flange of the corresponding rail.
2. A railway rail lock device comprising a transverse bar member composed of top and bottom parts adjustably connected, the top part being adapted at one end to be

passed beneath one rail and being provided with a hook member adapted to overlap the outer base flange of said rail, said top part being also provided adjacent to said end with a longitudinal aperture, and at the opposite end with a hook member adapted to overlap the inner base flange of the other rail, and the bottom part being adapted to be passed beneath the last named rail and being provided with a hook member adapted to overlap the outer base flange thereof and said bottom part being also provided at its opposite end with a hook member adapted to be passed upwardly through the aperture in the corresponding end portion of the top part and to engage the inner base flange of the corresponding rail, and means for locking the said parts in any position of adjustment.

In testimony that I claim the foregoing as my invention I have signed my name in presence of the subscribing witnesses this 22nd day of August 1917.

MICHAEL O'BRIEN.
